Dec 1783

Henry C. Thompson of New York, N.Y.
Assignor to
The Hartford Carpet Company
Letters Patent No 1755, dated June 16, 1863.

The schedule referred to in these Letters Patent and making part of the same.

To all whom it may concern:

Be it known I, Henry C. Thompson, of the City, County and State of New York, have invented or produced a new and original Design for a Pattern to be wrought into two ply Ingrain and other carpeting, in colors similar to those painted on the drawings accompanying

Dec. 1783

this specification, or in other colors substituted in the place of those painted on the drawings herewith: and I do hereby declare that the drawings accompanying this specification, do give and convey to anyone skilled in the art of Carpet weaving a more defined and thorough description of the nature of my invention than it is in the power of language otherwise to convey, and is sufficient to enable anyone skilled in the art of carpet weaving to weave my invention.

What I claim as my invention, and desire to receive by Letters Patent, is the configuration of the Design hereto annexed, when made by being inwrought into Isley's grain or other Carpeting, in the form as similar to the drawings accompanying this specification.
